UNITED STATES PATENT OFFICE.

CARL E. SHIELDS, OF ROCK ISLAND, ILLINOIS.

SAD-IRON.

1,199,119.

Specification of Letters Patent. Patented Sept. 26, 1916.

Application filed May 9, 1914. Serial No. 837,362.

To all whom it may concern:

Be it known that I, CARL E. SHIELDS, a citizen of the United States of America, and resident of Rock Island, Rock Island county, 5 Illinois, have invented a certain new and useful Improvement in Sad-Irons, of which the following is a specification.

My invention relates to sad irons of that type which are heated internally by jets of 10 flame and has for its principal object to provide a simple and improved structure in which the air chambers and air ducts are of the fewest possible number and of a character, in their simplicity of form, to greatly 15 reduce the cost of manufacture, by avoiding the excessive loss always incident to intricately cored castings.

Another object is to so form the air chamber and connect the air ducts thereto in a 20 manner to insure an abundant supply of air to the body of the iron and to be diffused therein in a manner to promote and support proper combustion.

These and other objects which will hereinafter appear I accomplish by the structure shown in the accompanying drawings in which,

Figure I is a perspective view of my improved sad iron, Fig. II is a side elevation 25 partly in section, Fig. III is an enlarged top plan view with the cover removed, Fig. IV is a cross section taken on line A—B of Fig. III. Fig. V is a cross section taken on line C—D of Fig. I.

Similar reference numerals refer to similar parts throughout the several views.

The iron can be made of any standard or desired form of outline and consists of the usual hollow body portion, a top plate or 40 cover to which is secured a handle, and the burner pipe entering the hollow body.

My invention is directed more especially to the manner of introducing the fuel—gas and air into the iron whereby perfect combustion is induced and maintained, producing a constant jet of blue flame at each opening in the burner pipe and which will not be affected by the usual jerky action to which irons are commonly subjected when in ordinary use. An insufficient quantity of air, sluggish circulation, coupled with an improper distribution thereof relative to the incoming gas, develop what are commonly termed "floating jets", that is the flame at 55 each orifice in the burner pipe is not constant—it is intermittent—going out and re-

lighting, thus permitting the constant escape of unburned gas, resulting seriously to the operator, especially if the iron is being used in a closed room. To insure a sufficient quantity, free circulation and proper distribution of air in the simplest possible manner, I provide the usual hollow body portion 1 of the iron with the extra thick bottom or floor 2 and the usual vertical sides 60 3. A plain, straight, roomy, rectangular air chamber 4 is cored out centrally of the floor throughout its length at the longest part thereof, the forward end being closed and terminating in the point of the body of the 70 iron, while the rear end pierces the rear wall and is open to the atmosphere. The upper wall of the channel is provided with the slot 4^a extending throughout its length and opening into the body 1. Radiating from 75 the side walls of the channel at both sides thereof, and preferably at an angle thereto, are the air-ducts 4^b extending through the thick bottom or floor 2 to the outside. The points of communication of these air-ducts 80 with the channel 4 are equally spaced along its length, thus insuring a full and constant flow of air through slot 4^a throughout its length. By locating the vertical walls of these air-ducts in a slanting position relative to the channel 4 they function as deflectors, reducing the tendency of the flames from the burner reaching out therethrough and scorching the material being ironed. 85 When these air ducts are located at right angles to the channel, it has been found that the flame very easily and very frequently reaches out beyond the sides of the iron, but when placed slantingly the tendency for the flame to so reach out is greatly checked. 90 By slanting some in one direction and others in the opposite direction an inflow of air is induced regardless of the direction in which the iron is being moved by the operator. The sides and rear walls of the body 100 of the iron are cut away at their upper edges as shown at 5 and 6. The cover 7 is secured to the top of the body by screws 7^a or in any other suitable manner, and to the cover is secured the usual handle 8. 105

Above the opening of channel 4 in the rear wall of the body portion is the centrally located opening 9 through which the burner pipe 10 passes. This pipe extends entirely across the hollow body of the iron and is securely screwed into the forward wall, closing the end thereof. Immediately outside of the 110

iron, the pipe is bent upwardly and provided at its free end with a properly formed nipple, provided with the usual air openings of a Bunsen burner, for the reception of a 5 rubber hose or gas tube. The pipe is further secured in proper position, relative to the body of the iron, and prevented from turning by the set screw 11 located in the bottom of the screw hole provided for the 10 cover screw 7^a. This burner-pipe 10 is positioned a suitable distance above the floor 2 and is provided with a series of openings or jets 12 throughout its length, near the bottom and on each side of the diametrical 15 center thereof.

To the under side of the lid or cover 7 is secured the baffle or deflector 13. This deflector is made of a single piece of metal and consists of the horizontal portion 13^a from 20 which, by proper slitting and punching, are formed the downwardly and outwardly extending wings 13^b. The deflector is secured to the underside of the cover by the same bolts that fasten the handle 8 thereto. It is 25 separated a suitable distance from the cover by the fillers 13^c. It is so positioned relative to the interior of the body of the iron that the free edges of the downwardly and outwardly extending wings come in close proximity to the side walls and floor, as shown 30 in dotted lines in Fig. IV, so that the heat arising from the burner and floor is deflected toward the center of the iron from which point it rises and escapes from the 35 outlets 5 and 6, through contact with the horizontal portion of the deflector. The heat is thus kept from contacting the cover direct, keeping it comparatively cool to the comfort of the operator. In thus baffling or 40 obstructing the outflowing heated air more heat units are given up and utilized in heating and keeping hot the thick floor of the iron, resulting in marked economy in consumption of fuel.

45 Thus described, it is seen I provide a sad iron in the heavy bottom of which is a plain rectangular passage or channel extending longitudinally thereof and having communication with the interior of the body of the 50 iron through an unbroken narrow slot extending practically the entire length of the channel. Through the open end of the chan-

nel and the numerous laterally and slantly extending ports or air ducts tapping the channel at regular intervals throughout 55 its length, an abundant and constant and evenly distributed supply of air is provided the burner, insuring proper combustion and an uninterrupted flame at every port in the pipe burner. The channel and lateral air 60 ducts being perfectly straight openings, the matter of manufacture is reduced to a simple problem. Where these air passages are of an intricate nature, requiring excessive and complicated cores, the loss of castings, 65 during their manufacture, due to "blows" often reaches a point as to render them commercially impossible.

What I claim is—

1. A sad iron comprising a hollow body, 70 a base, an air channel arranged centrally and longitudinally within said base, said air channel being closed at its forward end and open to the atmosphere at the other end, and horizontal air passages in said base arranged obliquely to and extending laterally from said air channel out through the sides of said base.

2. A sad iron comprising a hollow body, 80 a burner pipe provided with lateral openings, longitudinally and centrally positioned in said body, a cover for said body, a deflector provided with lateral openings in the upper portion secured to the under side of said cover and extending downwardly and outwardly to a point in close proximity to the floor and side walls of said hollow body.

3. A sad iron comprising a hollow body, a cover suitably secured to said body, a deflector consisting of a horizontal portion and integral wings bending downwardly and outwardly therefrom, said wings having upturned portions forming lateral openings in the upper portion thereof, a burner pipe passing longitudinally through said hollow body and positioned beneath the horizontal portion of said deflector and between the wings thereof.

Signed by me at Rock Island, Illinois, this 7th day of May, 1914.

CARL E. SHIELDS.
